FOREIGN PATENT DOCUMENTS

KR D2014-806 * 1/2014

Primary Examiner — Susan Bennett Hattan*Assistant Examiner* — Omeed Agilee(74) *Attorney, Agent, or Firm* — Lance M. Pritikin(57) **CLAIM**

The ornamental design for a medical vial holder, as shown and described.

DESCRIPTION

FIG. 1 is a front perspective view of a medical vial holder, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear perspective view thereof;

FIG. 9 is a front perspective view thereof showing the article next to two similar unclaimed medical vial holders;

FIG. 10 is a front perspective view thereof showing the article with an unclaimed bracket; and,

FIG. 11 is a rear perspective view thereof.

The broken lines in the Figures represent environmental structure and form no part of the claimed design.

1 Claim, 9 Drawing Sheets(56)
